Primary Examiner — Cynthia Ramirez*(74) Attorney, Agent, or Firm* — Perkins Coie LLP(57) **CLAIM**

The ornamental design for a winch, as shown.

DESCRIPTION

FIG. 1 is a perspective view of a winch showing our new design.

FIG. 2 is a front plan view thereof.

FIG. 3 is a back plan view thereof.

FIG. 4 is a right view thereof.

FIG. 5 is a left view thereof.

FIG. 6 is a top view thereof; and,

FIG. 7 is a bottom view thereof.

The broken lines shown in the figures are for the purpose of illustrating portions of the winch and form no part of the claimed design.

1 Claim, 7 Drawing Sheets(56)
